UNITED STATES PATENT OFFICE.

OSCAR F. FORSBERG, OF YONKERS, NEW YORK, ASSIGNOR TO WESTERN ELECTRIC COMPANY, INCORPORATED, OF NEW YORK, N. Y., A CORPORATION OF NEW YORK.

AUTOMATIC ELECTROMAGNETIC SWITCH.

1,279,854.

Specification of Letters Patent. Patented Sept. 24, 1918.

Application filed December 8, 1916. Serial No. 135,777.

To all whom it may concern:

Be it known that I, OSCAR F. FORSBERG, a citizen of the United States, residing at Yonkers, in the county of Westchester and State of New York, have invented certain new and useful Improvements in Automatic Electromagnetic Switches, of which the following is a full, clear, concise, and exact description.

10 This invention relates to automatic electromagnetic switches.

The object of the invention is to provide a rotating switch of the character described to quickly and effectively connect and disconnect circuits or parts of circuits by a uniform step or advance movement, and which shall automatically return to a normal position when its restoring circuit is closed.

15 The switch is provided with a plurality of normal positions and a feature of the invention is the means employed for stopping the switch in either of its normal positions upon restoration.

20 Referring to the drawings, Figure 1 is a front elevation, and Fig. 2 is a side elevation of a switch embodying the principles of this invention.

The structure and operating details of the switch will be more readily understood from 25 a consideration of the following description:

30 A yoke, or U-shaped member 1, which may be a metal punching, supports on brackets 2 a brush shaft 3. A channel plate 4 is fastened by its sides across the open end of the yoke 1 and supports one end of the magnet 35 M whose other end is fastened to the closed end 5 of the yoke 1. The armature 6 of magnet M is a flat plate provided with lugs 7 which are bent at right angles on either side 40 of the bottom of the armature. Through holes in these lugs 7 and in lugs 8 at the bottom of the open end of yoke 1 runs the pin 9, pivotally supporting the armature. The forward movement of the armature is restricted by the ends of the yoke 1 against which it rests when pulled up. Its backward movement is limited by the pin 10 projecting from the plate 11.

45 At the bottom of its closed end a portion 50 of the yoke 1 is bent to form the projection 12. On the lower side of this are piled a small Z-bar 13 and contact springs 14, 15, 16 and 17. The contact springs are separated by layers of insulation, and the pile 55 may be held together by a screw 18. A

spring 19 is stretched from the lower arm of Z-bar 13 to a projection 20 on back lug 7 of armature 6 to normally hold the armature retracted. A portion of the armature is bent to form the lever 21, at the end of 60 which is a collar of insulating material 22. This collar rests on one end of spring 15, and when the armature is pulled up breaks the contact between springs 14 and 15.

The brush shaft 3 carries a collar 23 which may be rigidly attached by a set screw or other means, not shown. The back end of the collar is enlarged into a disk in whose edge teeth 24 are cut. A pawl 25 is pivoted on a pin 26 which is carried by lugs 27 of 70 armature 6. A spring 28 holds the pawl in engagement with teeth 24, while a lug 29, carried by the armature, serves to prevent the fall of the pawl beyond the control of spring 28 in case of weakening of the spring. 75 An arm 30 is bent from the closed end of yoke 1 into a position such that it will limit the forward movement of the pawl 25 upon the energization of the magnet M to the amount necessary to rotate the brush shaft 80 3 through an arc subtended by a single tooth 24. A spring 45, fastened on the arm 30, rests on the teeth 24 and prevents retrograde movement of the brush shaft.

85 On the brush shaft 3 behind collar 23 is a collar 31 also rigidly held to the shaft. Pressed between collar 31 and a nut 32 are two strips of insulation, and between these strips is a thin metal disk which carries brushes 33. In the embodiment of the invention herein disclosed, these brushes are positioned at opposite ends of a diameter of the disk, and are two in number, but any desirable number could be provided. A metal feed plate 34, extending over an arc 90 of approximately 180 degrees, is insulatedly mounted on the rear bracket 2 in a position such that the lower brush 33 will wipe over it and that one of the brushes will be in contact with it in every position of the switch. 95 The other brush will wipe over the contacts 35, which are arranged in a semi-circular bank, and will rest squarely on a contact whenever the switch is at rest. Thus the feed plate will be successively connected 100 through the brushes to each contact as the brush shaft is rotated in response to the actuation of the magnet M.

105 The rear side of the yoke 1 is fastened to a plate 11, which is itself fastened by screws 100

36 to a plate 37. The plate 37 may be a metal punching, and has its upper end drawn so as to present an annular rim 38 whose front surface is parallel to the plane of the 5 brush disk and brushes 33. The contacts 35 are clamped between layers of insulation to the rim 38 by an annular strip 39. The ends of the contacts may be bent back over the edge of the rim 38, as shown in 10 Fig. 2, for convenience in connecting the terminals of the circuits associated therewith. The terminal connected with the feed plate 34 may be attached to the lug 40, provided on the feed plate for that purpose.

15 A bell-crank lever 41 set just inside the front side of the yoke 1 has at its lower end a yoke 42, the rear end of which carries a lug 46. The lever is pivoted on the pin 9, which runs through the lug 46 and the 20 lower end of the lever itself. The yoke 42 carries on its lower side a piece of insulation which rests on the contact spring 16. This spring 16 is stiff and by its pressure on the yoke 42 holds the lever 41 against a projection 43, which has been made by cutting out and bending inward a piece of the yoke 1. A cam 44 fixed at the front end of the collar 23 on brush shaft 3 will, by its bent portion at either end, engage the lever 41 25 twice in each revolution of the brushes. When so engaged the lever 41 will press the spring 16 down so as to connect it with spring 17. The normal position of the switch is that in which one brush rests on 30 the last contact to the left, and the other rests at the right-hand upper end of the feed plate. The cam 44 is adjusted so that when the brushes are in this position it will engage lever 41 and close the contact springs 35 40 16 and 17.

The switch as a whole may be mounted on a frame, not shown, by attaching to it the plate 37 in any suitable manner, and when so mounted the yoke 1 and all parts 45 carried by it may be readily removed by simply taking out the screws 36 which hold the plate 11 to the plate 37, such removal not necessitating any disturbance of the contact bank or its associated terminals.

50 The switch may be used as a counter or register, its magnet being intermittently energized in accordance with the number of contacts it is desired to have swept over before a circuit is completed from the feed plate terminal to some line terminating in a contact spring. When the desired contact is reached, the circuit is broken outside the switch and the brushes make the desired connection. To restore the switch to normal 55 60 when its use is over, it is only necessary to apply a source of current to the winding of the magnet, including the contact springs 14 and 15 in the circuit. The magnet will then interrupt its own circuit, stepping the 65 brushes around until cam 44 closes springs

16 and 17, and normal position is reached. To stop the brush in this position any well-known device may be employed to operate upon the closure of the springs 16 and 17, and break the circuit through the magnet M. 70

What is claimed is:

1. The combination in a switch mechanism of a U-shaped supporting member, a series of contacts, a feed plate, a rotatable brush shaft mounted on said supporting member, a plurality of brushes carried by said shaft arranged to engage and make connection between the feed plate and the successive contacts of said series, each of said brushes having a normal position, an electromagnet mounted between the arms of said supporting member, an armature therefor pivotally mounted between the arms of the supporting member, means carried by said armature for operating said brush shaft, a set of spring contacts, and means controlled by the brush shaft when said brushes are in their normal positions for actuating said contact set. 80

2. The combination in a switch mechanism of a U-shaped supporting member, a series of contacts, a feed plate, a rotatable brush shaft mounted on the supporting member, a plurality of brushes carried by said shaft arranged to engage and make connection between the feed strip and the contacts of said series, each of said brushes having a normal position, an electromagnet mounted between the arms of said supporting member, a pivot pin fixed to the opposite arms of the supporting member, an armature for said electromagnet mounted on said pivot pin, means carried by said armature for operating the brush shaft, a set of spring contacts, a lever for operating said contact set mounted on said pivot pin, and means for actuating said lever when any one of said brushes is in its normal position. 90

3. The combination in a switch mechanism of a U-shaped supporting member, an arcuate series of contacts, an arcuate feed member, a rotatable brush shaft supported by the opposite arms of the U-shaped member, brushes on said shaft arranged to engage and make connection between the feed member and the contacts of said series, said brushes each having a normal position, an electromagnet mounted on the U-shaped member between the arms thereof, a pivot pin supported across the free-ends of said arms, an armature for the electromagnet carried by said pivot pin, means on said armature for operating the brush shaft, a contact set, a lever mounted on said pivot pin and arranged to actuate said contact set, and means including a cam secured on the brush shaft for operating said lever when one of said brushes reaches its normal position. 110 115 120 125 130

4. The combination in a switch mechanism of a U-shaped supporting member, a series of contacts, a feed plate, a rotatable brush shaft supported by the opposite arms 5 of the U-shaped member, brushes on said shaft arranged to engage and make connection between the feed plate and the contacts of said series, said brushes each having a normal position, an electromagnet mounted 10 on the U-shaped member between the arms thereof, a pivot pin supported across the arms of said U-shaped member, an armature for said electromagnet mounted on said pivot pin, means on said armature for 15 operating the brush shaft, sets of spring contacts, means on said armature for actuating one of said contact sets at each energization of the electromagnet, a bell-crank lever pivoted on said pivot pin and arranged to 20 actuate another of said contact sets, and means carried by the brush shaft for operating the bell-crank lever when each of said brushes reaches its normal position.
5. The combination in a switch mechanism of a U-shaped supporting member the 25 arms of which are provided with parallelly extending integral brackets, a series of stationary contacts, a brush shaft rotatably supported by said brackets, brushes on said shaft arranged to coöperate with said contact series, each brush having a normal position, a stepping magnet mounted on the U-shaped member between the arms thereof, an armature therefor pivoted to the free 30 ends of said arms, means on said armature for operating the brush shaft, a contact set, a bell-crank lever pivoted between said arms and arranged to actuate said contact set, and a cam attached to the brush shaft for 35 operating said lever when any one of said 40 brushes is in its normal position.

In witness whereof I hereunto subscribe my name this 7th day of December A. D., 1916.

OSCAR F. FORSBERG.
